CAP SPINNING TRAVELER

Ernest K. Bauer, Meadville, Pa., assignor to
American Viscose Corporation, Wilmington,
Del., a corporation of Delaware

Application April 24, 1945, Serial No. 589,961

2 Claims. (Cl. 57—127)

1

The present invention relates to cap spinning apparatus for winding and twisting yarns of natural or artificial filaments or fibers.

In conventional cap spinning systems, the yarn rubs over the stationary edge or rim of the cap while moving both transversely and peripherally with respect to it. On the other hand, in ring spinning, a traveler is provided, with respect to which the yarn moves transversely, whereas the yarn does not take the wear or friction involved in the peripheral motion with respect to the ring. Instead, the traveler takes this portion of the friction. However, a ring-twister has a disadvantage in the extra time and care needed to effect lacing.

It is the principal object of the present invention to provide a cap spinning apparatus in which the yarn receives the wear and friction only with respect to the transverse motion of the yarn relative to the cap edge while at the same time retaining ease of lacing. Other objects and advantages of the invention will be apparent from the drawing and the description thereof hereinafter.

In general, the objects of the invention are achieved by providing the edge of the cap with a traveler which holds the yarn out of contact with the stationary edge of the cap while the yarn moves the traveler peripherally with respect to the cap edge.

A more complete understanding of the invention may be had by reference to the accompanying drawings, in which—

Figure 1 is an elevation, partly in section, showing one illustrative embodiment of the invention;

Figure 2 is a perspective of a part of the embodiment of Figure 1 on a somewhat enlarged scale;

Figures 3 and 4 are plan and elevational views of the traveler of the embodiment of Figures 1 and 2;

Figure 5 is a perspective illustrating the modification;

Figures 6 and 7 are plan and elevational views of the traveler of the modification of Figure 5;

Figure 8 is an elevation showing the mounting of another form of traveler upon a cap edge;

Figure 9 is a section taken on lines IX—IX of Figure 8;

Figure 10 is a modification of Figure 9, in which the slope of the bottom surface of the cap edge has a smaller angle than in Figure 9;

Figure 11 is a perspective view of the traveler shown in connection with Figures 8 to 10; and

2

Figure 12 shows a modification in which the traveler takes the form of a rotating ring mounted upon the cap edge.

Referring to Figures 1 to 4, a bobbin 2 is mounted upon a driven hollow spindle 3 through which the upright rod 4 extends and carries at its upper end the cap 5. Relative reciprocating motion in a vertical direction is imparted to the bobbin and cap, either one of which may be held at a fixed level while the other moves vertically with respect thereto. The yarn proceeds downwardly through a suitable guide 6 about the bottom edge of the cap to the bobbin on which it is wound.

In accordance with the present invention, the cap is provided with a traveler 7 which may take the form of a bent wire having two trailing legs 8 which fit slidably within upper and lower grooves 9 provided about the periphery of the cap 10. This foot member may be the bottom edge of the cap itself, or it may be a separate piece as shown, adapted to be threadably supported upon the base or bottom of the body portion of the cap. The traveler 7 has portions extending from the two legs 8 and peripherally outwardly from the grooves. These extensions reach around the outer edge of the cap to a bent portion which projects downwardly from the rim. It will be observed that the yarn in passing around the cap makes no contact with it, but passes around the portion 11 which connects directly with the downwardly bent portion 12. Lacing is effected merely by passing the yarn to the bobbin under the cap regardless of the position of the traveler at the time of lacing. Rotation of the bobbin causes winding of the yarn and causes the yarn to form a balloon between the guides 6 and the edge of the cap. This balloon quickly moves around the edge of the cap until it catches up with the depending portion 12 of the traveler which is then slid peripherally of the cap during the rest of the period of operation.

In Figure 5, an annular skirt 13 is threaded over a shoulder portion 14 of the cap 5a. The skirt 13 is provided with an undercut groove 15 adapted to receive the legs 16 of the traveler 17. The construction of traveler 17 is such that it may be used with bobbins which rotate in either direction, the outwardly bent shoulders 18 serving to keep the yarn from making contact with the edge of the cap or its skirt by virtue of the fact that they project outwardly from the edge of the cap. The shoulders are joined by the

loop 19, against one side of which the yarn is adapted to ride during operation.

In Figures 8 and 9, a skirt 20 may be threadedly supported upon the bottom edge of the main cap body. This skirt has a flange 21 which is preferably inclined so that its bottom surface slopes inwardly and upwardly. An angle of 60° is shown in Figure 9, whereas an angle of about 10° slope is shown in Figure 10. The particular angle depends upon the weight of yarn, the speed of traverse and related factors.

The traveler 22 has a yarn-engaging depending portion 23 extending downwardly from a three-legged hook. Two of the legs reach around under the flange 21 and hook over that edge at spaced points therealong, preferably on opposite sides of the depending portion 23. The third hook reaches around in the front of the flange. The traveler thus operates virtually as a sliding saddle or yoke. The leg which lags with respect to the direction of rotation of the bobbin, has a portion 24 extending downwardly below the edge of the flange 21 and the yarn is adapted to travel about this portion of the traveler, so that it is kept out of contact with the stationary cap.

Figure 12 illustrates a modification in which the lower rim of the skirt of a cap 5b is provided with a race 25 adapted to receive a plurality of anti-friction ball bearings 26. An outer race is provided within a skirt 21 and accommodates balls 28. Between the two sets of balls 26 and 28, there is provided a ring 29 having a depending yarn-engaging guide 30 for directing the yarn about the rim of the stationary cap without contact therewith. The travelers can take other forms and can be made from wires or from cast or stamped metals. The rotating ring of the type shown in Figure 12 may be an accurately machined casting in order to obtain the minimum of friction. The particular metals of the travelers may be selected to obtain a minimum amount of friction with respect to the guideways or grooves in which they are adapted to travel on the rim of the cap. The design of any particular type of traveler can vary considerably, always taking into consideration the desideratum

to balance as much as possible the resultant force of centrifugal action and gravity upon the traveler, with the resultant force of the yarn as it travels thereabout to the bobbin, in order to approach as closely as possible the idle condition of a floating traveler or sled.

It is to be understood the description hereinabove is illustrative only, and that changes and variations may be made without departing from the spirit and scope of the invention as defined in the appended claims.

I claim:

1. Cap spinning apparatus comprising a non-rotatably mounted cap, an annular guideway on the lower rim of the cap, a traveler, guide means on the traveler arranged to co-operate with the guideway, said traveler having a portion below, and extending in the general direction of, the lower rim of the cap comprising a yarn-guiding surface for holding the yarn out of contact with said rim and a portion bent downwardly from said yarn-guiding surface so that it extends in the way of the yarn as it passes under the cap.

2. Cap spinning apparatus comprising a non-rotatably mounted cap; an annular flange on the lower rim of the cap; and a traveler having a plurality of arms hooked about opposite edges of the flange, a portion projecting downwardly from the flange into the way of the yarn as it passes under the cap and a shoulder extending back from said downwardly projecting portion having a yarn-guiding surface below the rim of the cap for holding the yarn out of contact with said rim.

ERNEST K. BAUER.
